ANTENNA

Lester C. Van Atta, Winchester, Mass., assignor
by mesne assignments, to the United States of
America as represented by the Secretary of the
Navy

Application March 5, 1946, Serial No. 652,190

7 Claims. (Cl. 250—33.65)

1

This invention relates to antennas for radar systems, and more particularly to means for obtaining a radiation pattern closely approximating the relationship $Csc^2 \theta$ where θ is the angle measured from the axis of the radiating means.

In search radar systems it is generally desired to produce an antenna pattern which will enable a continual and simultaneous search of both near and far objects remotely disposed on the earth's surface or at equal elevations relative to the antenna, without tilting the antenna. Such a pattern is known in the art as a $Csc^2 \theta$ distribution.

Accordingly, the primary object of this invention is to construct an antenna arrangement adaptable for search radar system use to provide a continual search of near and far objects.

Another object of this invention is to provide an antenna which produces $Csc^2 \theta$ radiation pattern, wherein the angle θ is measured with respect to the axis of directivity of the reflector and in one quadrant of a plane intersecting said axis.

Other objects and features of the present invention will become apparent upon a careful consideration of the detailed description when taken with the accompanying drawings in which:

Fig. 1 is a front view of the antenna showing the structural features thereof according to one embodiment of the invention; and

Fig. 2 is a cross-sectional view of Figure 1, taken along section line II—II.

Referring to the drawings, a half-paraboloid 11 is placed upon horizontal ground plate 12. Wave guide horn feed 13 is constructed and located with its aperture at the focal point 14 of half-paraboloid 11. A thin, narrow metallic strip 15 is placed on ground plate 12 and attached to half-paraboloid 11.

The polarization of the feed at 14 is such that the electric field intensity vectors are normal to ground plate 12. Half paraboloid reflector 11 together with reflecting ground plane 12 produces an effective aperture when viewed from points above reflecting ground plane 12, and a 180 degree phase discontinuity in the middle of the aperture, which results in a radiation pattern very roughly approximating the $Csc^2 \theta$ pattern. This configuration is produced by the combined effects of the reflection pattern of the half paraboloid and the radiation pattern caused by currents set up in the ground plate. The presence of the ground plate has the effect of producing a radiation component which apparently emanates from beneath the ground plane, thus causing the 180° phase discontinuity. A detailed discussion of this phenomena, as applied to a some-

2

what different antenna configuration, is presented on pages 9-99 of Principles of Radar, 2d edition, 1946, McGraw-Hill Book Company, Inc. The introduction of the strip 15 and the control 5 of the position and dimensions thereof gives additional control for shaping the space radiation pattern to produce a more closely approximated $Csc^2 \theta$ coverage. The introduction of the strip 15, however, also has a marked effect on the total reflection back into the antenna feed. It is therefore necessary in the adjustment of strip 15 to compromise these two effects. If strip 15 were quite small its important effect would be on the impedance match between the antenna and the 10 wave guide feed 14. If the strip is larger the effect on the radiation pattern becomes more important.

The invention described in the foregoing specification need not be limited to the details shown, 20 which are considered illustrative of one embodiment of the invention. For example, the wave guide horn feed may be replaced by a flared horn, di-pole or any other conceivable radiating means. The strip 15 need not be flat, but may be cylindrical, conical, may have double curvature, or may be left out altogether. No attempt has been made to exhaust all possible variations, but the scope 25 of the invention is defined by the appended claims.

30 What is claimed is:

1. A radio antenna system comprising a radiating means, a half-paraboloid reflector, a metallic ground plate positioned in a horizontal plane, said half-paraboloid being placed on said ground plate with the axis of the half-paraboloid in said ground plate, said radiating means being mounted upon said ground plate at the focus of said reflector, said antenna system being adapted to direct radiant energy along a divergent path 35 whereby an unsymmetrical radiation pattern is produced.

2. A radio antenna system comprising a radiating means, a half-paraboloid reflector, a metallic ground plate positioned in a horizontal plane, 40 said half-paraboloid reflector being placed on said ground plate with the axis of the paraboloid in said ground plate, and a metallic strip attached to said ground plate and said reflector along the junction thereof, said antenna system 45 being adapted to direct radiant energy along a divergent path whereby an unsymmetrical radiation pattern is produced.

3. An antenna system as in claim 2, in which the dimensions of said metallic junction strip 50 are chosen with reference to the wave length of

the radiant energy, to make the combination of radiation patterns from said reflector and said strip produce a radiation pattern which varies substantially as the square of the cosecant of the angle measured from the radiation axis of the antenna.

4. A radio antenna system comprising, an open ended metallic wave guide, a metallic ground plate positioned in a horizontal plane, a half paraboloid section reflector, said reflector being mounted upon said ground plate with the axis of said reflector lying in said ground plate, said open ended metallic wave guide being mounted upon said ground plate with the open end at the focus of said reflector, the electric vectors of the energy supplied by said wave guide being directed perpendicular to said ground plate, and a metallic strip attached to said ground plate and said reflector along the junction thereof, the dimensions of said metallic strip being chosen with reference to the wave length of the radiated energy to make the combination of the radiation patterns from said reflector and said metallic strip produce a radiation pattern which varies in the axial plane of said reflector perpendicular to said ground plate substantially as the square of the cosecant of the angle measured from the axis of said reflector.

5. A radio antenna system comprising, a radiating means, a metallic ground plate positioned in a horizontal plane, a half-paraboloid section reflector, said reflector being mounted upon said ground plate with the axis of said reflector lying in the ground plate, said radiating means being mounted at the focus of said reflector, the electric vectors of the energy supplied by said radiating means being directed perpendicular to said ground plate, and a metallic strip attached to said ground plate and said reflector along the junction thereof, the dimensions of said metallic strip being chosen with reference to the wave length of the radiated energy to make the combination of radiation pattern from said reflector and said metallic strip produce a radiation pattern which varies in the axial plane of said reflector perpendicular to said ground plate substantially as the square of the cosecant of the angle measured from the axis of said reflector.

6. A radio antenna system comprising a radiating means, a metallic ground plate, a half-paraboloid section reflector, said reflector being mounted upon said ground plate with the axis of said reflector lying in said ground plate, said radiating means being located at the focus of said reflector, the electric vectors of the energy supplied by said radiating means being directed perpendicular to said ground plate, said configuration of reflector and ground plate being adapted to produce a radiation pattern which varies in the axial plane of said reflector perpendicular to said ground plate approximately as the square of the cosecant of the angle measured from the axis of said reflector.

7. A radio antenna system comprising, a radiating means, a metallic ground plate, a half paraboloid section reflector, said reflector being mounted upon said ground plate with the axis of said reflector lying in said ground plate, said radiating means being located at the focus of said reflector, the electric vectors of energy supplied by said radiating means being directed perpendicular to said ground plate, and a metallic strip attached to said ground plate and said reflector at the junction thereof, the dimensions of said strip being chosen with reference to the wave length of the radiated energy to produce an optimum impedance match between said reflector and said radiating means.
